[57] CLAIM

The ornamental design for a message holder for use with an imitation flower or the like, substantially as shown and described.

DESCRIPTION

FIG. 1 is a front perspective view of a message holder for use with an imitation flower or the like showing my new design;

FIG. 2 is a rear perspective view thereof; and

FIG. 3 is a side elevation thereof.

The broken lines representing the imitation flower are shown for illustrative purposes only.

FIG. 1

FIG. 3
